UNITED STATES PATENT OFFICE.

WILLIAM J. FRYER, OF NEW YORK, N. Y.

WATER-CLOSET.

SPECIFICATION forming part of Letters Patent No. 532,656, dated January 15, 1895,

Application filed October 31, 1892. Serial No. 450,435. (No model.)

To all whom it may concern:

Be it known that I, WILLIAM J. FRYER, a citizen of the United States, residing in the city and county of New York, in the State of 5 New York, have invented a certain new and useful Improvement Relating to Water-Closets, of which the following is a specification.

I have discovered an improved form of the parts. Instead of making the rim or top of 10 the bowl in a plane, as usual, I form it high at the back, low at each side, a little higher at each side of the front and still higher in the middle of the front. When, as is the case 15 with many forms of water-closet, it is desired to have the water passage extend quite around the interior of the rim, I cause the water passage to be correspondingly undulated. The same effect as usual is produced with such water passage by making the nu- 20 merous holes or a continuous narrow opening in the bottom thereof through which a thin sheet of water is discharged to wash the entire interior of the bowl.

The seat may be of wood, or analogous 25 easily cleanable material which is a good non-conductor of heat. Instead of making it plane, as usual, I form it undulated to correspond approximately to the rim of the bowl. I provide a slop safe and cover correspond- 30 ingly curved.

The improvement may be applied with all 35 the ordinary constructions of bowls and all the ordinary arrangements of the operating mechanism. There may be a cover to close down over the seat when desired.

The accompanying drawings form a part of this specification and represent what I consider the best means of carrying out the invention.

40 Figure 1 is a central vertical section from front to rear, showing the upper portion of the bowl with the seat in position for use. Fig. 2 is a corresponding plan view, and Fig. 3 is a vertical section of a portion on the line 45 3-3 in Figs. 1 and 2. Fig. 4 is a vertical section of a portion showing a modification.

Similar letters of reference indicate corresponding parts in all the figures where they appear.

50 A is a bowl, certain parts being designated,

when necessary, by super-numerals, as A'. It is provided with an internal lip or casing extending around on the inside of the top, formed integral with the bowl, and provided with an ordinary water connection W to supply water to wash the interior of the bowl. 55 The rim or upper edge of the bowl and the lip instead of being in a plane are curved, as shown in the figures, the back A' of the bowl being high, the sides and a considerable portion of the front being low, but the sides being lowest, and the central portion A² of the front being high. The height at the center of the front should be about equal to that at the back. The front, except at and near the 60 center, may be about one inch lower than the back. The sides may be one-and-a-half inches lower than the back.

The seat is marked B. It may be of soft mahogany, or other suitable wood, hinged as 70 usual at the back edge. Certain portions of the seat are designated, when necessary, by super-numerals. B' is the high portion at the back and B² the high portion at the center of the front. The remainder of the seat 75 is low. The form of the under face of the seat B, B', B², corresponds to the upper edge of the bowl. The upper face is smoothly curved. It may be produced by removing portions of the wood from a sufficiently thick 80 plane piece, or it may be produced by bending and holding until cold a thoroughly steamed board. The lid D, hinged a little farther back, as usual, is adapted to serve the usual functions of a cover by completely covering the 85 whole, when lowered. It should be similarly curved or it may be made with angular forms approximating to the curve of the seat. I have shown both conditions.

My improvement provides a seat which is 90 comfortable for both sexes and for all ordinary variations in size and form. When used by persons who are ill, or careless from any cause, it reduces the risk that any urine shall be thrown over the front of either the bowl 95 or seat.

E is a slop safe, of cast or wrought iron of sufficient thickness, provided with a low rim E' on its upper face at the outer edge, and enameled on its whole upper surface. It is 100

curved to correspond to the top of the bowl. It lies between the bowl and the seat in the same manner as the ordinary plane safe lies, but curved to adapt it to the curved form of the bowl rim and seat. The slop safe serves its usual functions in arresting and leading into the bowl any water which may be thrown thereon. The high back performs an important duty in decreasing the risk of soiling 10 that portion of the seat under any circumstances.

Modifications may be made without departing from the principle or sacrificing the advantages of the invention. The cover may 15 be plane, with a hanging rim at the front and sides properly formed to make a close joint with the seat. Such is outlined in Fig. 4.

The slop safe E may be omitted and the seat allowed to match down close to or even

to touch the rim of the bowl if preferred in 20 any case.

I claim as my invention—

In a water-closet, in combination with the water connection W, and bowl A, having its rim waved, and provided with a correspondingly waved internal lip for distributing the water, a slop safe E, inclined inward and having a raised rim E' and a raised back, and a seat B and cover D, all correspondingly waved, and arranged for joint operation, substantially as herein specified.

In testimony that I claim the invention above set forth I affix my signature in presence of two witnesses.

WM. J. FRYER.
